UNITED STATES PATENT OFFICE

HELGE A. BORRESEN, OF CHICAGO, ILLINOIS, ASSIGNOR TO UNITED-CARR FASTENER CORPORATION, OF CAMBRIDGE, MASSACHUSETTS, A CORPORATION OF MASSACHUSETTS

LATCH FASTENER

Application filed March 16, 1925. Serial No. 15,848.

My invention relates to latch fasteners and more particularly to a fastener comprising a pair of separable members, one of which has a locking member that is adapted to engage 5 the other member to hold said members locked together.

Reference is hereby made to my co-pending application Serial No. 607,345, filed December 16, 1922, which application contains 10 claims generic to the type of fastener illustrated and described in my present application. However, it is my intention to claim in the present application, both broadly and specifically, improvements herein disclosed 15 over my earlier filed application.

It is a purpose of my invention to provide a fastener of the above mentioned character that is provided with a locking member that is adapted to engage a headed member, said 20 locking member being mounted in a housing and being slidable into and out of locking engagement with the headed member.

It is a further purpose of my invention to provide a fastener of the above mentioned 25 character having a one piece housing comprising a flanged front portion and a rear cover portion connected together by a reduced portion acting as a hinge during closing of said housing.

It is still a further purpose of my invention to provide a device of the above mentioned character comprising a locking member or latch that is adapted to be automatically moved to unlocking position by engagement 30 of the material upon which the same is mounted with a portion of the latch or locking member to move said latch or locking member to unlocking position.

It is another purpose of the invention to 40 provide a device of the above mentioned character in which the locking means is held in locking position by means of a spring or other resilient member wherein said spring or other resilient member is initially tensioned in assembling the device.

It is also a purpose of the invention to provide a device of the above mentioned character in which the locking latch is formed of a portion of the spring to thus provide a simple 45 and cheap, yet efficient construction.

It is a particular purpose of my invention to provide means whereby said spring or other resilient means is automatically tensioned in assembling the device, said automatic tensioning being preferably accomplished by providing a one-piece housing having portions that are adapted to assume positions opposite each other when the housing is in assembled or closed position, one of the portions of the housing receiving the locking member and the other having means for holding the spring or other resilient member so that when said portions are brought into opposed relationship, the ends of the spring will be moved relative to each other so as to tension the same. In the preferred form, the locking member is provided with a projection receiving one end of the spring and the one portion of the housing is provided with a pair of hook-like projections over which the other end of the spring is hooked when the housing is in open position. Then by swinging the portion of the housing having the hook-like projections toward the other portion of the housing and toward the locking member in assembling the device, the ends of the spring are brought closer together, placing the same under initial tension automatically. This greatly reduces the cost of the device.

It is another purpose of my invention to provide a fastener comprising a headed member having an enlargement adjacent the base thereof that is adapted to be received in a recess in the housing of the member carrying the locking means to prevent movement of the housing transversely of the headed member.

It is also a purpose of the invention to provide a locking member that is in sliding engagement with the inner face of the housing so that any strains on the locking member are transmitted directly to the housing.

It is another purpose of my invention to provide a fastener of the above mentioned character that has a socket member secured to one member which the fastener is intended to secure to another member and a device carrying a locking latch provided with a projecting portion having a hook-like formation thereon adapted to enter said socket and lock

itself therein so as to secure said members together.

It is a further purpose of the invention to provide a device of the above mentioned character having a socket portion that is undercut or which has an overhanging lip portion with which the hook-like projection is adapted to engage to secure the parts together.

It is still another purpose of the invention to provide the hook-like projection on a slidably-mounted-locking member that is mounted within a housing, said locking member being held in locking position by suitable resilient means and being movable out of locking position by movement of a portion of the housing.

It is another purpose of the invention to provide a locking member of the above mentioned character movable out of locking engagement with the socket member by movement of the housing which is also movable independently of the housing.

Other objects and advantages of the invention will appear as the description of the accompanying drawings proceeds. However I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a face view in elevation of one form of my improved fastener showing a fragment of the material upon which the same is mounted;

Fig. 2 is a rear elevation similar to Fig. 1; Fig. 3 is a front elevation of the headed member forming a portion of the separable fastener showing a fragment of the material upon which the same is mounted;

Fig. 4 is an enlarged fragmentary view in section taken substantially on the line 4—4 of Fig. 1;

Fig. 5 is a section taken substantially on the line 5—5 of Fig. 4;

Fig. 6 is a plan view of the blank from which the housing of my improved fastener is made;

Fig. 7 is a view showing the housing in open position as the spring is assembled therewith;

Fig. 8 is a side elevation of the locking latch employed in this form of my invention;

Fig. 9 is a view similar to Fig. 1 of another form of my invention;

Fig. 10 is a view similar to Fig. 2 of the form of the invention shown in Fig. 9;

Fig. 11 is a face view in elevation of a socket member with which the member shown in Fig. 10 is adapted to co-operate showing a fragment of the material upon which the socket member is mounted;

Fig. 12 is an enlarged fragmentary view in transverse section of the member shown in Fig. 10 showing a fragment of the socket member in co-operating relation therewith;

Fig. 13 is a section taken on the line 13—13 of Fig. 12 on a reduced scale;

Fig. 14 is a rear face view of my improved fastener with the outer portion of the housing removed;

Fig. 15 is a plan view of the blank from which the movable member of the housing is made;

Fig. 16 is a view partly in section and partly in elevation of a stud provided with a socket member with which the member shown in Fig. 10 co-operates;

Fig. 17 is a perspective view of the locking member employed in the device shown in Fig. 12;

Fig. 18 is a face view of the stud shown in Fig. 16 viewed from the left end thereof;

Fig. 19 is a side elevation of the movable housing member before the same is closed;

Fig. 20 is a view similar to Fig. 15 of a modification;

Fig. 21 is a view partly in plan and partly in section of said modification; and

Fig. 22 is a fragmentary side view of a portion of the spring latch employed.

Referring in detail to the drawings, in Figs. 1 to 8 inclusive is shown a fastener comprising a housing having the top wall portion 20 and the bottom or rear wall portion 21. Said housing is formed from a blank such as that shown in Fig. 6, the portion indicated by the numeral 20 in Fig. 6 representing the portion of the blank forming the top of the housing, and the portion bearing the numeral 21 that forming the back cover or rear 21 of the housing. The top forming portion is formed with a flange 22 forming the side wall portions of the housing and the portions 20 and 21 are connected by means of a reduced portion 96 acting as a hinge to permit swinging of the cover 21 toward the flanged body portion 20 to close the housing. Co-operating with the housing is a back plate 23 which is secured to the housing by means of the prongs 24 and 25 projecting from the housing which are clinched over the plate 23, as will be clear from Figs. 2 and 4, said prongs being preferably mounted in recesses 26 in the plate 23. When the housing and the plate 23 are secured together, the supporting material 27 is clinched between said housing and said back plate, said plate 23 being provided with an upturned curved peripheral flange portion 28 engaging said material, thus avoiding any sharp edges at the periphery of the plate 23.

Mounted within the housing is a slidable latch or locking member 29 which is adapted to slidably engage the inner face of the top 20 of the housing. An upstruck projection 30

is provided on the member 29 adjacent the elongated opening 31. The projection 30 is arcuate, as will be clear from Fig. 5, and is concavo-convexly curved as will be clear 5 from Figs. 4 and 5, but is provided with a substantially flat surface 32 at which the shoulder 33 on the under face of the rounded head 34 provided on the stud 35 is adapted to engage, said stud 35 being provided with 10 a threaded portion 36 screw-threadedly engaging a supporting member 37. It will be seen that the opening 31 accommodates the head 34 of the stud and permits sliding movement of the locking member 29 transversely 15 of the stud 35.

Said locking member is provided with a pair of shoulders 38 that are adapted to engage with the side wall portions 22 adjacent the opening 39 in the side wall portion of 20 the housing. The reduced shank portion 40 of the locking member extends through the opening 39 and is held in closed engagement with the top 20 of the housing due to the provision of the depending flange or lip 41 provided on the rear wall 21 of said housing leaving only a slot slightly larger than the portion 40 of the member 29 through which said portion 40 projects. The projecting portion of the member 29 terminates in a curved 25 transverse head portion 42 which is curved both transversely and longitudinally, as will be clear from Figs. 4 and 5 so as to provide a rounded surface for engagement by the material 27 whereby the slideable locking member or latch 29 can be moved in a direction to move the overhanging lip portion 30 away from the head 34 of the stud 35 to disengage 30 said locking member from said head. The locking member has a rearward projection 43 that is adapted to engage with the wall portion 22 to limit the unlocking movement 40 of the locking member 29.

The locking member is normally held with the shoulders 38 in engagement with the wall 45 portions 22 and with the lip portion 32 in engagement with the rear face 33 of the head 34 by means of the spring having the curved portion of relatively large radius 34 engaging with the projection 30 on the locking member 29 and having a portion of sharper curvature 35 joining the portion 34 with a similar portion of relatively greater curvature 46 which joins the portion 47 lying substantially parallel to the side wall portion 50 of the housing and which spring is provided with a transversely extending substantially straight portion 48 connected with the portion 47 by the abrupt bend 49. The spring 55 is preferably put under initial tension so as 60 to always exert a spring pressure on the locking member when the device is assembled. The holding means for the straight portion 48 of the spring is so arranged that the spring 65 will be automatically tensioned during assembly of the device.

It will be noted upon reference to Fig. 6 that a pair of prongs 50 is punched out of the material of the rear portion 21 of the housing. The prongs 50 are in the position shown in Fig. 7 when the rear portion 21 of the housing is bent partly over toward the front portion 20 thereof. Said prongs then serve as hooks in back of which the straight portion 48 of the spring may be placed, said portion being then confined between the springs 50 and the wall 21. As the rear wall 21 is swung further toward the top forming portion 20 to close the housing, the prongs 50 and the straight portion 48 of the spring are moved toward the left in Fig. 7 or toward the projection 30. This continues until the rear portion 21 of the housing is substantially parallel with the front portion 20 thereof. At this time, the prongs will be in the position shown in Fig. 4 and the spring 80 will be under tension due to the fact that the distance between the portions 44 and 48 thereof will have been materially decreased causing the portion 46 to move away from the portion 44. The prongs 50 now act as 85 an abutment to prevent the movement of the portion 48 of the spring toward the wall portion 22 of the housing.

The rear plate 23 is provided with an annular depression or recess 51 within which the enlargement 52 on the stud 35 is adapted to seat to prevent transverse displacement of the housing relative to the stud, the projection of the enlargement 52 within the recess in the member 23 being limited due to the 90 overhanging lip portion 53 with which the member 52 engages. The member 52 is preferably made hexagonal so as to serve as means for engagement of a tool therewith to screw the stud into position in the member 37. A 95 guiding finger or projection 54 is also provided on the member 23 that enters the elongated opening 55 provided in the member 21, said finger or projection 54 acting to guide the head of the stud 34 in its movements into 100 and out of engagement with the member 30 and prevent catching of the same on the member 21. Upon reference to Fig. 5, it will be seen that the projection 30 is provided with a curved edge portion 55 adjacent the 105 stud 35, this preventing any sliding of the latch member out of locking position under the head of the stud.

In Figs. 9 to 18 inclusive another form of my invention is shown in which a housing having a top wall portion 60 having a depending peripheral flange 61 and a back cover or rear wall portion 62 is provided. The top wall portion is preferably completely closed and the bottom wall portion 62 is provided with a pair of parallel slots 63, a rectangular opening 64 and a slightly oblong opening 65. This is clearly shown in Fig. 15 in which the blank from which the housing is made 110

is shown. From Fig. 15, it will be seen that a reduced portion or tongue 97 connects the portions 60 and 62 of the blank and serves as a hinge as the cover 62 is swung toward the flanged body portion 60.

Mounted within the housing for sliding movement relative thereto is the locking member 66. A base plate 67 is secured to the bottom of the housing 62 by means of the ears 68 that extend through the slots 63 and which are bent over on opposite sides of the locking member or latch 66. The ears 68 guide the locking member 66 in its sliding movements on the bottom 62 of the housing.

Said locking member is provided with a projection 69 having a hook-like end portion 70 that is adapted to engage with the overhanging lip portion 71 provided on the socket member 72, said lip portion being preferably annular. The socket member 72 preferably projects from a base 73 that carries the prongs 74 for securing the same to any suitable mounting material 75. The socket member 72 is shown in Fig. 11 as being provided with such a base for securing the same to a piece of flexible material. Sometimes, however, it is desirable to provide a socket member that can be secured in a framework member of any automobile or similar part and for this purpose, the arrangement shown in Figs. 16 and 18 may be used in which the screw member 76 is provided with a head having a hexagonal portion 77 and provided with a socket portion 78 having an overhanging lip portion 79 which is preferably annular in form as described in connection with the lip portion 71. The hook-like member 70 would engage with the lip portion 79 of the member 76 in the same manner as it engages with the lip portion 71 of the member 72.

The slideable locking member 66 is further provided with a depending flange or lip 80 which passes through the opening 64 and which limits the movement of the locking member relative to the housing in both directions. The member 66 is further provided with a prong or a lip portion 81 extending in the opposite direction to the flange or lip 80 which is turned over as indicated in Figs. 12 and 13 so as to secure one end of the spring 82 to said member 66. The spring 82 is provided with a plurality of bends, as will be clear from Fig. 13, three such bends being provided therein. The opposite end of the spring 82 is secured to the base member 67 by means of the prong 83 extending upwardly therefrom and bent over said spring 82 as shown in Fig. 12. The prong or hook 83 extends through the opening 64, as will be clear from Figs. 12 and 13. A pair of rearwardly extending fingers 84 is also provided on the member 66, said fingers extending on opposite sides of the opening 64 and passing on opposite sides of the prong 83.

The base member 67 is provided with a plurality of prongs 85 which pass through suitable openings 89 in the washer or back plate 86, the material 87 to which the fastener is secured being clamped between the members 67 and 86. Said prongs preferably lie in recesses 88 in the member 86 so as to be flush with the surface thereof.

The annular groove 91 is provided on the washer or plate 86 to accommodate the enlargement 77 on the stud 76 or the rib 90 on the member 73. The member 67 is, of course, provided with an oblong opening 92 through which the projection 69 passes and the washer 86 is provided with an opening 93 to accommodate the projection 69. An annular inturned flange 94 is provided on the member 86 to provide a recess within which the end of the socket member 72 or 78 projects to prevent movement of the back plate 86 of the fastener and the portion 67 of the housing relative thereto.

It will be seen from the above, that the hook-like member 70 can be disengaged from the lip portion 71 by moving the housing comprising the portion 60, 61 and 62 to the left in Fig. 12. The movement of the housing will carry the locking member 66 along with the same due to the fact that the end of the rectangular opening 64 will engage with the lip 80, the prongs or ears 68 sliding in the slots 63 when this occurs, the length of the slots of course limiting the movement of the housing relative to the base member 67. It is, however, unnecessary to move the housing to engage the hook-like member 70 with the socket member 72 or 78 as the curved cam-like face 95 will engage with the lip 71 and will move the member 66 against the tension of the spring 82 both relative to the housing and the base plate 67, the lug or projection 80 moving in the slot 64 when this occurs.

The length of the stud or projection 69 or the member 30 will depend upon the thickness of the material 87, it being obvious that a longer stud has to be provided for thicker material as indicated in dotted lines at 69' in Fig. 17, or as indicated at 30' in Fig. 8.

In assembling the device the members 66 and 67 as well as the spring 82 are assembled with back cover or rear wall portion 62, the same extending substantially at right angle to the portion 60 at this time as shown in Fig. 19. Then the housing is closed by swinging the portion 62 about the hinging portion 97 until the parts are in the position shown in Fig. 12.

In Figs. 20, 21 and 22 a modified construction of fastener is shown in which the housing comprises the main body forming portion 100 and the rear wall or cover forming portion 101, these being connected together by a reduced connecting portion 102 as clearly shown in Fig. 20, this figure showing the blank. The body forming portion 100 is

formed in a die so as to have the flange portion 103 thereon, the portion 102 serving as a connecting hinge portion between the cover 101 and the body portion 100. The blank is 5 further provided with a plurality of holding prongs 104 that are adapted to engage with the material upon which the member is mounted for holding the same in place. The cover portion 101 is provided with an 10 oblong opening 104 through which the stud 106 having the head 107 thereon extends.

A prong or finger 108 is provided on the cover member 101 which is adapted to be engaged with the end portion 109 of the spring 15 wire member 110 in a similar manner to which the prong 50 engaged with the portion 48 of the spring in the device shown in Fig. 5. The spring wire member 110 has a portion forming substantially to the inner contour 20 of the container formed by the member 100 being spaced sufficiently therefrom to obtain the desired action of the spring. Said member has an offset portion at 111 that is adapted to engage with the adjoining portion of the 25 housing and with a further outwardly offset portion 112 that serves as an operating portion. From the offset portion 112, a sharply curved portion 113 extends which is connected with the more gradually curved portion 30 114 that is adapted to engage under the head 107 of the stud 106 so as to interlock therewith the portion 114 serving as the latching portion of the spring wire member 110, the latch 29 shown in Fig. 5 being disposed with 35 in this form of the invention.

In order to engage under the head of the stud, no matter what the extent of said head into the housing may be, the spring wire member 110 is suitably formed to engage 40 under said head, being offset to engage therewith as indicated at 115 in Fig. 22 when this is necessary, the amount of offset being greater as indicated in dotted lines at 115', if the stud extends a shorter distance into the housing 45 and being less as indicated at 115, if the stud extends a greater distance into the housing. The housing is provided with a lip portion 116 that extends toward the cover 101 and a depending lip portion 117 that extends 50 toward the body portion 100, thus forming a guide for the offset portion 112 which extends on opposite sides of said lips.

It will be evident from the above, that in the form shown in Figs. 20 to 22 inclusive 55 a very cheap and simple construction is obtained which has all the advantages of the separate latch and spring but in which the spring wire member forms a spring portion, an operating portion and a latching portion.

Having thus described my invention what I desire to claim and secure by United States Letters Patent is:

1. A device of the character described comprising a headed member and a member 60 adapted to engage said headed member, said

last member comprising a housing having an aperture therein adapted to receive said headed member, a locking device and spring means for holding said locking device in locking engagement with said headed member in said housing, said housing having a recess in its outer surface adjacent said headed member and said headed member having an enlargement seating in said recess to hold said last mentioned member from movement 75 transversely of said headed member.

2. A device of the character described, comprising a housing having top and bottom portions adapted to be brought into opposed relationship to form the housing, a latch engaging one of said portions, a projection thereon, a spring engaging said projection and means on one of said portions engaging said spring to tension the same when said portions are brought into opposed relationship. 80

3. A device of the character described, comprising a housing having top and bottom portions adapted to be brought into opposed relationship to form the housing, a latch flatly engaging one of said portions, a projection thereon, a spring engaging said projection and means on said other portion engaging said spring to tension the same when said portions are brought into opposed relationship. 90

4. A device of the character described, comprising a housing having top and bottom portions adapted to be brought into opposed relationship to form the housing, a latch engaging one of said portions, a projection thereon, a spring engaging said projection and prongs on said other portion engaging said spring to tension the same when said portions are brought into opposed relationship. 100

5. A device of the character described, comprising a housing having top and bottom portions adapted to be brought into opposed relationship to form the housing, a latch engaging one of said portions, a projection thereon, a spring engaging said projection and a pair of hook prongs on said other portion engaging said spring to tension the same when said portions are brought into opposed relationship. 110

6. A device of the character described, comprising a housing having top and bottom portions adapted to be brought into opposed relationship to form the housing, a latch slidably engaging one of said portions, a projection thereon, a spring having a bowed end portion engaging said projection and prongs on said other portion of said housing, said spring having a portion engageable over said prongs before moving said portions of said housing into opposed relation, whereby said spring is tensioned when said opposed portions are moved into opposed relationship. 120

7. A device of the character described, comprising a housing having top and bottom portions adapted to be brought into opposed relationship to form the housing, a latch slidably engaging one of said portions, a projection thereon, co-operating means on said latch and housing, for limiting the movement of said latch within said housing, a spring, having a bowed end portion engaging said projection, and prongs on said other portion of said housing, said spring having a portion engageable over said prongs before moving said portions of said housing into opposed relation, whereby said spring is tensioned when said opposed portions are moved into opposed relation.

8. A fastener of the character described comprising a housing, a latch in said housing, a spring controlling said latch, and a headed member adapted to be projected into said housing to engage with said latch, said latch having an offset portion projecting toward said headed member to engage under the head thereof, said spring engaging said offset portion and having a portion engaging a side wall of the housing.

In witness whereof, I hereunto subscribe my name this 6th day of March A. D. 1925.

HELGE A. BORRESEN.
